DIVAN

John H. Jordan, Jr., 8124 S. Crandon Ave.,
Chicago, Ill. 60617

Filed Aug. 29, 1969, Ser. No. 18,920

Term of patent 14 years

Int. Cl. D6—01

U.S. Cl. D15—11

FIG. 1.

FIG. 2.

FIG. 1 is a front perspective view of a divan showing my design; and

FIG. 2 is a view in side elevation taken from the right of FIG. 1.

The back of the divan is conventional in configuration.

I claim:

The ornamental design for a divan, as shown and described.
